METHOD AND MEANS FOR THE RECORDATION DUPLICATION AND REPRODUCTION OF SOUND AND PICTORIAL IMAGES

Carl Louis Oswald, New York, N. Y., and Warren Dunham Fester, Washington Township, Bergen County, N. J., assignors, by direct and mesne assignments, to Kinatome Patents Corporation, a corporation of New York

Original application October 29, 1928, Serial No. 315,761. Divided and this application August 21, 1933, Serial No. 686,155. In Great Britain October 26, 1929

17 Claims. (Cl. 88—16.2)

The present invention relates broadly to the art of recording sound upon light sensitive material and the reproduction of sound therefrom by photo-electrical means, but it will be readily understood that it may be applied to many other uses. Our invention is particularly applicable to so-called film-playing phonographs, both for initial recordation and subsequent reproduction, particularly with films which carry sound images in conjunction with visual images, as in the so-called "talking movies". Our invention also includes the method, and means for the production, of duplicate sound records, or positive prints from a master record or negative, for combination with pictures or use synchronously therewith, such method and means being useful steps in the accomplishment of the final result of improved tonal and pictorial reproduction.

The present application is divisional from our co-pending application, Serial Number 315,761, filed October 29, 1928, and allowed May 25, 1933, which upon September 26, 1933, matured as Patent Number 1,928,392, and relates primarily to the joint recordation, duplication and reproduction of both sound and pictorial images.

A primary object of our invention is to secure the accurate and faithful translation of sound waves into photographic images and of the resulting photographic images into sound waves. We provide improved method and means whereby recorded sound may be reproduced more accurately and pleasurable than heretofore has been possible in conjunction with pictures. A related object is the photographing upon film from which sound is to be reproduced, preferably concurrently with the photographing thereupon of the pictorial images, of lines or masses which are so clear and distinct, and of such uniform density, that sound waves reproduced from them will be clear, distinct and true. We also provide a method for the translation of these reproducing lines, masses or signals into audible sound waves, which reduces to a minimum any possibility of distortion or blurring, such translation taking place concurrently with the projection of the pictorial images. In our parent application, to which reference is made above, we describe and claim similar method and means applied to the initial recordation, subsequent duplication, and final reproduction of sound images alone.

A principal object of our invention is the provision of method and means whereby in a film carrying sound and pictorial images, the quality of neither will be sacrificed to the demands of the other, but both sound and picture will be presented accurately and pleasingly. 5

Another object of our invention is to make possible the use of photographic images in lines or mass formations, representing sounds which it is desired to record or reproduce, which photographic images may be materially smaller than such as now are common in the art and hence of particular usefulness in connection with motion picture films of 16 millimeters or 9 millimeters in width or of some other size primarily 10 designed for home use and which are of less than the so-called theatrical standard of 35 millimeters width. Obviously upon such films, which because of economy and other commercial conditions, are now well established for domestic 20 use, the area which is available for the sound image is very much reduced. As a consequence the difficulties which have arisen from ill defined photographic images, representing sound impulses, when these are imprinted upon 35 millimeter films, have been greatly exaggerated when such images have been correspondingly reduced in size for use upon the small area of the 16 millimeter or other so-called substandard film 25 which can be taken from the area devoted to the pictures. Our invention makes it possible to secure upon 16 millimeter film, for example, as clear and accurate sound images as those which previously have been secured upon 35 millimeter 30 film, and applies with corresponding effect to film 35 of even smaller dimensions.

Another object of our invention is the reproduction of duplicate copies or prints of combined sound and picture films in which the picture record is printed in accordance with the photographic requirements of the sound record, thus making it possible in a single operation, for example, to print the pictorial portion very soft with a minimum of contrast and the sound portion very hard with a maximum of contrast, thus 40 much improving the quality of the reproduction, audibly and visibly, of the combined sound and pictorial record. 45

Another object of our invention is to add to the electrical acoustic means commonly em- 50

ployed in the initial recordation, subsequent duplication and final reproduction of sound images certain photographic methods, means, and technique in such manner as to secure improvement in the quality of sound translation and retranslation, and at the same time to permit full liberty in the handling of the pictorial image. By the employment of the apparatus and the means and methods herein described, it is possible to assure the integrity of the latent sound image as of the moment at which it is implanted upon the photo-sensitive material without in any way sacrificing the quality of the accompanying pictures. A further object of our invention is the treatment of that latent image by such chemical and physical means, chosen with due regard to the means and methods which had been employed to implant the latent image and the characteristics of the particular photo-sensitive material employed, as will retain in the stable and completed sound image the quality imparted by such previous steps in the process, likewise without injury to the pictorial image.

Another object of our invention is to provide apparatus for the taking, printing and projecting of talking pictures, which may be simply constructed and maintained, and a method which is simple and inexpensive.

Other objects, advantages and characteristics of our invention are apparent from the following description, the attached drawings and the subjoined claims. Although we are showing one preferred embodiment of each of the several phases of our invention, it will be readily understood that we are not limited to these particular constructions and processes as changes can be readily made without departing from the spirit of the invention or the scope of our broader claims.

It will be readily understood by those skilled in the art that our invention applies to sound apparatus generically. It will also be readily understood that our invention may be applied to any art in which the accurate and controlled recordation of a photographic image is useful or necessary in the exercise of control or translation by means of light.

In the drawings:

Figure 1 is a diagrammatic representation of diffraction occurring as light passes through an aperture, greatly exaggerated for the purpose of clarity.

Figure 2 is a diagrammatic section along the surface II-II of the film 5 of Figure 1.

Figure 3 is a diagrammatic view of one form of our invention as embodied in a sound recording instrument.

Figure 4 is a diagrammatic view of one form of our invention as embodied in a sound reproducing instrument.

Figure 5 is a diagrammatic representation of an aperture plate and gate which we may use as a common gate, for both series of images.

Figure 6 shows our invention applied to an optical reduction printer with a common gate for both pictorial and sound images.

Figure 7 shows means employed by us to maintain a light source at a constant temperature and point of incandescence.

Throughout the drawings and specifications like characters apply to like parts. For the purpose of greater simplicity, like parts which are duplicated in various embodiments of our invention receive the same reference numerals except where clarity demands otherwise.

In carrying out our invention, we employ light

of a predetermined wave length. We select light of that particular rate of vibration which has the photographic qualities which are desirable for the particular result which is to be obtained. For example, when we select light from the visible spectrum, we employ monochromatic light of a selected color or wave length, for the recordation of the photographic image representing the sound wave.

From among the many photographic emulsions which are available, we are not compelled to choose in accordance with the limiting requirements of white light but are enabled to use in each employment of our invention the photographic emulsion which is best suited to the requirements of the particular conditions then applying and to employ in each instance that particular form of light which will be best suited to the particular emulsion deemed most suitable.

We select the developer for the latent image so implanted upon the selected emulsion by use of light of a selected wave length with due regard both to the particular characteristics of the particular emulsion and its reaction to the selected wave length and also to the peculiar demands of that portion of the film bearing the pictorial image as well as of that portion of the film bearing the sound image, in case both images are at once or ultimately implanted upon the same strip. Thus it will be seen that we choose that particular combination of light, emulsion, and developer which will result in the most satisfactory sound and pictorial images under the given conditions.

In present common practice, polychromatic light, ordinarily spoken of as white light, is employed in apparatus using visible light for the electrical recordation of sound. Even with the use of a better photographic technique than is now common, polychromatic light would still cause many of the difficulties to which reference has already been had and will later be made.

For purposes entirely different from those embraced within or pertinent to our invention, it has been proposed to employ visible colored images for use as sound records. We do not use colored images as part of or in carrying out our invention of sound recordation. We use what is ordinarily known as colored light, but the latent images produced thereby, when rendered stable and visible by development, are what are known as black and white. They have none of the characteristics, requirements or purposes of colored images or photography. It will therefore be understood by those skilled in the art, that our invention does not require the use of the special and expensive films and apparatus, which have been proposed to be used for purposes different from our own, nor are we limited by the many photographic and practical difficulties associated with the use of so-called colored films.

When reference in this specification or in the claims which are a part hereof is made to "black-and-white" films, it is understood that such terminology is used with the meaning common in the motion picture art. Such "black-and-white" films may be colored by tinting or toning or any other similar process, whether carried on as supplementary to the regular development and fixing or otherwise. Moreover, the term may be used to include films which are made upon a base which is colored or tinted, provided the emulsion used thereon is one of those ordinarily associated with the making of black-and-white images if used with an ordinary white or gray base. It will

be understood, of course, that when it is desired to use color for the pictorial portion of the film, our process may be applied to that portion of the negative which is reserved for the symbols representing sound.

It will be noted in the subjoined claims that the step of moving the film is not in all cases specifically included, although, as well known to those skilled in the art, and as is stated herein, sound is ordinarily recorded upon, printed upon, and reproduced from, a moving film. Such omission in the claims of an obvious step is to avoid encumbering the claims with unnecessary words, since, wherever necessary, the inclusion of this obvious step will be understood.

The processes of the electrical recordation of sound upon a photographic film or similar light sensitive surface are of course well understood. The film or other light sensitive material is moved continuously at a uniform speed and upon it, generally through a slot, a light is projected, varying in accordance with the amplitude of the sound waves which are being recorded. Thus there is imprinted upon the light sensitive surface a series of images the photographic density of which varies in accordance with the variations of the sounds which are being recorded. The resulting images may appear to the eye to be a series of lines of varying intensity. These lines in the negative indicate by means of greater density the nodes of the sound waves and by less density the anodes of the sound waves, or, in case of the use of photo-electric cells of a certain less usual type to control the fluctuation of the light, the reverse is true.

As a matter of convenience, it is to the above-indicated method of sound recordation that reference will most often be made. It will be readily understood, however, that our invention is equally applicable to any form of sound recordation which depends upon the implantation of photographic images upon a light sensitive material, whether, for example, such images take the form commonly known as variable density or variable area or any other form.

Similarly it will be understood that the reproduction of photographically created sound records of any type depends upon the passage of light therethrough and its impingement upon material the resistance of which to an electrical current varies in accordance with the light thrown thereupon, this electrical current telephonically creating sound waves. Consequently any lack of exactitude in the translation of the sound image into the photographic image will be reproduced in the translation of the photographic image back into the sound image, together with whatever additional inaccuracy or lack of clarity may exist because of the imperfections of this process of re-translation.

Polychromatic light, the use of which our invention eliminates, causes much of this inexactitude and many of these imperfections.

Figure 1 illustrates in a much exaggerated form the edge diffraction which is caused by passing polychromatic light through a narrow slot of the type commonly used in the art. The degree of diffraction which results from passing white light over an edge is directly proportioned to the lengths of the several waves which make up the light. Thus the rays of the longer wave lengths are diffracted to a greater extent than are those which are of lesser amplitude. In Figure 1, 1 represents a beam of polychromatic light of which 2 is the axis.

In this and many of the following drawings, for convenience we show the light as a straight line such as 1. It will be understood that, except as definitely stated, we do not limit ourselves to an optical system of any particular nature. The light may be projected, by any suitable optical system, in the form of parallel, divergent or convergent light. If desired, a mirror or other reflecting element, not shown, may be employed behind the light source. This light in passing through the opening 3 in the aperture plate 4 is diffracted in accordance with the wave lengths of its component parts. Thus the infrared rays 6 and 6' show the maximum diffraction, the visible red rays 7 and 7' the next largest degree of diffraction, the yellow rays 8 and 8' a lesser diffraction, the blue rays 9 and 9' the least amount of diffraction of the visible rays and the ultraviolet rays 10 and 10' the least diffraction, the degree of diffraction of the sub-primary colors not being shown.

As these rays of varying wave lengths fall upon the film 5, as is well illustrated in Figure 2 of the drawings, there are transverse bands of the light sensitive emulsion which are subjected to rays of different colors. Every light sensitive emulsion has varying degrees of sensitivity to different colors. As a result of such varying sensitivity, while the entire portion of the emulsion between the lines 11 and 11' is acted upon with approximate uniformity by the white light, the bands from 10 and 10' to 6 and 6', both inclusive, are acted upon in degrees varying according to the sensitivity to color of the particular photographic emulsion which is being used at the time. As a result the portions of the entire line or mass which lie between 11 and 6 and 11' and 6' respectively are lacking in uniform photographic density, the portion between 11 and 11' being more nearly uniform. In other words, the edge is not clear and straight. It is in effect ragged and "muddy". As a result, when a reproduction of the photographic image which is bounded by such an edge is used to actuate a photo-electric cell in the reproduction of sound, what the auditor hears is likewise unclear, "muddy" and blurred. It will be readily recognized that any blurring of a recorded photographic image caused by such diffraction will result in a corresponding blurring of the sound which is reproduced therefrom.

We have found that much of the difficulty in the past blamed generally upon "diffusion", and even photographic "grain", is in reality due to the lack of a correct photographic definition caused by fringing colors, which in turn are the result of diffraction as stated above.

It will be readily understood that the more narrowly the slot is restricted in size, the more pronounced will be such imperfections.

In Figure 3 we show diagrammatically one embodiment of our invention applicable to a sound recording system such, for example, as one which employs an immovable light supplied by an electric current varying in accordance with the amplitude of the sound waves to which a diaphragm is subjected.

In Figure 3, the intensity of the light at source 12 in operation is constantly varied in accordance with the amplitude of the sound waves which are being recorded. Any one of the many well known devices to accomplish such purpose may be employed, as for example a microphone 13 connected with any suitable type of current controlling device indicated generically as 13'. Since

the method of controlling the variations of the light source 12 in accordance with the sound waves is well known and forms no part of the present invention, it is neither described nor claimed.

The light 1 emitted by source 12, we pass through an appropriate color filter 14, the slot 3 in the aperture plate 4 and on to the film 5. Since the optical system, and the method 10 of feeding the film form no part of the present invention and since any of several well known optical systems and film feeding methods may be employed, we do not describe or claim them.

The exact filter to be used will depend upon the 15 photographic characteristics of the emulsion selected. It will be readily understood that with the use of any monochromatic light all of the area of the film which is exposed or illuminated at the same instant will be of practically uniform 20 density. For example, if we elect to employ light of approximately 4000 Angstrom units, we will use a filter 14 adapted to prevent the passage of all light other than such as will register between 9 and 9', inclusive, as shown in Figures 1 and 2. 25 The image so created upon the film will have sharp demarcation along the lines separating band 9 from band 9' from band 8'. That is, each illuminated or exposed area will be clearly and sharply defined and its so-called photographic contrast great. Irrespective of the type 30 of monochromatic light employed, the sharpness or differentiation or contrast will be increased over such as obtained with polychromatic light and the "raggedness" caused by the use of such 35 light largely eliminated. It should be noted, however, that the relative excellence of the result will depend upon the selection of the wave length particularly appropriate to the photographic emulsion selected. In recent practice, in order 40 to overcome difficulties caused by the so-called "grain" of the emulsion, relatively slow emulsions, such as, for example, those of 120 according to the rating of Hurter and Driffield, have been recommended for sound films. By the use 45 of photographically active wave lengths, such as for example those in the vicinity of 4000 Angstrom units, we secure with such a slow emulsion in a relatively short period of exposure the same results as others secure in a much longer and 50 hence impractical period of exposure.

It will be understood that instead of using rays of one wave length only, we may employ rays of a group of related wave lengths.

In carrying out our invention we may simultaneously record the images representing sound upon the same film as that upon which the images representing action are recorded. Or we may make records of each series of images upon different films and subsequently impose the images 55 representing sound upon an unoccupied portion of the film bearing the original images representing action. Or we may make separate record or negative films for the sound and action images and duplicate both such series of images upon different portions of one positive film.

If we use a common record or negative film for both sound and action images, as is shown for purposes of illustration herein, we may provide a camera lens CL through which light 1' from the action or scene being recorded is focussed 60 through the aperture 3' upon the film 5. It will, of course, be understood that a certain portion of the film is reserved for the action images and another separate portion for the sound images, 65 the respective apertures 3' and 3 being so designed

as to direct the light beams 1 and 1' upon the appropriate portions of the film.

In those cases in which the sound and pictorial records are simultaneously placed upon the same film, we may prefer to use an emulsion rated at 5 between 120 and 200 according to the scale of Hurter and Driffield. An emulsion of a speed of 180 upon that rating may be taken for purposes of illustration.

For an emulsion of such a speed, with a latent 10 image of the sound record produced by monochromatic light, as for example that of approximately 4000 Angstrom units, and the pictorial portion produced by polychromatic light, we prefer to use glycin, known as gamma oxyphenyl or 15 as gamma oxyphenyl-amido-acetic acid, as the developing agency. Under such conditions, glycin will produce the necessary contrast in the sound image and at the same time build up the half tones of the action image. It will be 20 readily understood by those skilled in the art that for pleasing results in reproduction the sound images require great contrast and the action images full gradation. If, however, polychromatic light is used for the sound images, the glycin development would tend to reduce the contrast in 25 the sound images to a point which will result in unsatisfactory reproduction. If a hydrochinone developer is used, the sound image made with light of a wave length of 4000 Angstrom units 30 would be satisfactory but the pictorial image, which is of course always recorded by polychromatic light, would be unpleasantly harsh. If a hydrochinone developer is used with a sound image made by polychromatic light, a period of de- 35 velopment is necessary in order to secure proper contrast in the sound image which will still further increase the unpleasant harshness of the pictorial image.

The use of glycin is desirable also because it 40 tends to reduce the grain. As is well known in the art, a slow emulsion has less grain than a more rapid one. Hence we prefer to use as slow an emulsion as is consistent with the demands of the pictorial image. Only with the use of monochromatic light is it possible to secure, in a way practical in sound recordation and reproduction, the use of both of these factors, namely a relatively slow emulsion and glycin development, which tend to eliminate the difficulty caused by 45 grain.

In glycin development, the following stock solution may be prepared:

Water, H ₂ O	ounces	32
Sodium sulphite, Na ₂ SO ₃ , anhydrous	grams	360
Glycin, C ₆ H ₄ CHNHCH ₂ COOH	do	120
Sodium carbonate, Na ₂ CO ₃ , anhydrous	grams	360

The chemicals should be dissolved in the above 60 order. The water should preferably be of a Fahrenheit temperature between 100 and 120 degrees.

For use with the emulsions of the speed stated above, such stock solution may be diluted at the ratio of one part stock solution and three parts 65 water. The film may be developed for thirty minutes, preferably at about 65 degrees Fahrenheit. After such development, the usual steps of washing, fixing, and final washing may be taken.

We prefer to keep the film totally immersed during the entire period of development in order to minimize oxidation fog. We have found that the elimination of such fog is an important item in securing clear and sharp sound images. Glycin 75

is a developer which produces a minimum of such fog, but to prevent the possible formation of such fog, we may prefer to use a bath of pinakryptol green, in a dilution of one part to five thousand parts of water, before the development as by the use of glycine.

It will be understood that we do not restrict ourselves to the particular formulae, chemicals, or emulsion speeds stated above, but that we state 10 the same for purposes of illustration.

For purposes of further illustration, it may be assumed that we wish to make a combined sound and pictorial record of waves breaking upon the shore of the sea. In order that we may secure 15 full color and gradation values, we may prefer to use an emulsion having the color sensitivity commonly known as panchromatic together with a filter for the pictorial portion of the film. Such a filter may be of a yellow color and of the type 20 commonly known in the photographic art as K3. For the sound image, we may prefer to use a light of approximately 4000 Angstrom units because such a light, in combination with a panchromatic emulsion, produces great contrast. The poly- 25 chromatic light, modified as is well known in the art by the K3 filter produces an image which is soft and pleasing. Glycin development of such a film gives satisfactory results in both portions. In this case, however, with the use of panchro- 30 matic film, we may prefer to use a preliminary bath of pinakryptol green diluted at the ratio of one part to four thousand parts of water.

For the purpose of still further illustration, it may be assumed that it is desired to produce a 35 combined sound and pictorial film under conditions which require a fast emulsion. The action to be recorded, for example, may be rapid or light conditions poor and not subject to control as in a studio. An emulsion of a speed on the Hurter 40 and Driffield scale of over 450 may be chosen. Under such conditions, a monochromatic light of 4000 Angstrom units may be too rapid in its action. In such cases, we prefer to use for the sound recordation a filter which will transmit 45 light of a suitable wave length or group of wave lengths as, for example, any wave length or group of wave lengths between 4500 to 5800 Angstrom units, depending upon the particular emulsion employed. Thus we are enabled to give to the 50 operator definite filters for use with definite emulsions, rather than depending upon adjustments in the field of the light source for the sound record.

It has been proposed in the past to make use of 55 special emulsions which, after the images implanted thereon have been developed and rendered visible, have peculiar characteristics of permeability by or absorption of light waves of particular wave lengths in combination with 60 the photo-electric cell of particular characteristics in a sound reproducing instrument. It will be understood that we use regular stock photographic films known as black-and-white, which can be readily and cheaply obtained 65 throughout the world, choosing such films, however, in accordance with the purely photographic characteristics thereof which are useful for the particular purpose set forth in this specification. Our choice of an emulsion of a particular speed 70 is conditioned by the photographic characteristics of the latent images which can be implanted thereon by the use of light of a particular wave length, and the photographic characteristics of the visible and stable images which can be de- 75 veloped from such latent images. Although our

invention can be applied to those types of apparatus in which separate films are employed for the sound and pictorial records, it is also equally applicable to those types of apparatus in which one film is used to carry both such records. It 5 will be readily understood that such a single film bearing both such records must be chosen, exposed, developed, duplicated and projected in accordance with all the requirements of both such records. As is made clear throughout this 10 specification, our method is so adapted to create a single film which bears both types of records thereupon.

Figure 4 diagrammatically shows our invention as applied to the reproduction of sound. 15 The light 1 from a constant light source 12 passes through the appropriate color filter 14, the slot 3 of the aperture plate 4 and the film 5, and impinges upon the photo-electric cell 18 of its equivalent, which actuates the sound pro- 20 ducing device 20 through the control element 19. Since the optical system, the method of film feeding, the light sensitive electrical element and the sound producing device and its control form no part of the present invention and are 25 well known in the art, they are not further described or claimed. Light 1' is shown as passed from a lamp house LH through a projection lens OL and gate 3' and the film 5 and upon a screen S, as is well understood in the art. 30

The same considerations apply to the effect of light upon light sensitive electrical elements as upon the light sensitive emulsions. Mixed or polychromatic light impinging upon a photo- 35 electric cell causes variable and untrue sound reproduction, since the photo-electric cell is differently responsive to each color. The results obtained by our use of monochromatic light for translation of light into sound are analogous to or the same as those described above for the 40 translation of sound into light.

Another factor improving reproduction and recordation renders the use of monochromatic light for sound translation superior to any means heretofore employed. As is well known in the 45 art, the sensitivity of photo-electrical elements commonly varies both in accordance with the color of light and its intensity. Thus any change in voltage or temperature of the theoretically constant light source 12 may cause a color change 50 as well as an intensity change, varying "white" light from red through yellow to in many cases even blue. The photo-electrical element is affected by such change in color as well as by the reduction in intensity. Later we describe means 55 for removing one cause of change in color but it is obvious that better results are obtained by the removal by the use of monochromatic light of one of the variants so described.

It is apparent that the ability so to record 60 tonal variations in very great detail and almost microscopic size will render possible a vastly increased range of tonal recordation and likewise a notable improvement in the detail of recorded sound. 65

It is also apparent that the increased intensity of light available for delivery at the surface of the film 5 through the means described will render possible the use of whatever loss photo- 70 graphically active rays of light and photo- graphically slower emulsion which may be 75 deemed desirable because of the so-called "grain" or other photographic difficulties, all of which above advantages, methods and means are such as will be fully known to and understood by those

skilled in the art without further description or explanation in detail.

Figures 5 and 6 illustrate diagrammatically the application of our invention to printing or 5 duplicating apparatus.

The negative film 30 and the positive film 45 may be fed in any manner well known in the art, as through a common gate or through separate gates with an optical element intervening. 10 Figure 5 shows a gate 41 having an aperture 42 including a space left unimpeded for the pictorial images on frames 34 of the film and a light filter 44 adapted to cover the area opposite which the sound images 39 of the film are fed. The 15 negative therefor is seen as traveling through the gate 41 which is intersected by light 1 from the source 12, "white" light passing through the picture area and monochromatic light of any desired characteristics passing through the 20 sound area. As shown in Figure 6, optical redirection through the element 48 directs the combined sound and picture images upon the positive film 45, which may if desired be of a size smaller than that of the negative.

25 It will of course be understood that the filter 44 may if desired be placed in the gate through which the positive film is fed. It will also be understood by those skilled in the art that as illustrated and described at length in our parent application Serial Number 600,322, filed March 21, 1932, as divisional from our said parent case, we show separate elements for the simultaneous printing of the sound image and the light image or for successive printing of the two images from 30 the one negative upon one positive, such printing exposure taking place successively.

The type of gate shown for purposes of illustration only herein is best adapted for printing from a duplicate negative which has been 40 "timed" so that fluctuation of the printing light for the picture area to compensate for differing densities is not required. It will be understood, however, that any desired form of printer may be used to carry out our invention. It will 45 also be understood that the form of gate shown in Figure 5 may be used for recording or reproduction with the sound aperture covered by the filter 44 conventionally spaced from the picture aperture.

50 The necessity of a hard contrasting image for the sound portion of the film has been emphasized above. Such images, however, in the pictorial portion of the film generally prove very unpleasant. It will be thus seen that our invention makes it possible to use whatever type of light is desirable for the sound record portion of the film and whatever type of light is desirable for the pictorial portion.

According to one preferred embodiment of 60 our invention, we employ ultraviolet light for any and all of the purposes above set forth in connection with visible monochromatic light. Ultraviolet light possesses the advantages which we have stated for monochromatic light in the 65 visible spectrum and in addition shows less diffraction than any of the wave lengths of the visible spectrum and is furthermore extremely active photographically. In carrying out our invention by means of the use of ultraviolet 70 light, we employ any suitable light source encased in quartz, or a light source which will emit visible and ultraviolet light under normal atmospheric conditions, such as, for example, the electric arc and the so-called Nernst lamp. 75 In carrying out our invention in accordance

with this exemplification, we use a light source 12 of some such type as we mention above in such structures as those diagrammatically represented in Figures 3, 4 and 6, and in the manner described in connection therewith. In 5 every instance in which a lens or other similar optical element is employed in connection with ultraviolet light it must of course be constructed of quartz, as is well known in the optical art.

In order to combine aperture plate and filter, 10 with the use of ultraviolet light, we may employ the aperture plate which is illustrated and claimed in our said parent application.

To secure improved and stable translation of sound images into light images, the theoretically 15 constant light source may be maintained at a point which is actually constant, or approximately constant, as is illustrated, for example, in Figure 7 of the drawings. Obviously the difficulties caused by the change in color of the 20 light caused by the fluctuations of the light source are removed by the use of monochromatic light. A further embodiment of our invention prevents material change in light intensity, 25 such changes causing analogous difficulties.

A common cause of change in intensity of the theoretically constant light source is found in temperature changes which decrease or increase the degree of incandescence of the light element. The common expedient of warming the light 30 source by turning on the current in advance of its use does not meet the difficulties caused by later changes in temperature caused by conditions which later develop. We have found that the opening of a door or window in a room in 35 which apparatus is being used will change the visible characteristics of the light. The means shown for example in Figure 7 definitely controls the heat of the theoretically constant light source.

40 A light source shielded and controlled as is here set forth may be used as described in any or all of the previously described exemplifications of our invention. The arrangement herebelow described is of particular usefulness under any 45 conditions under which an approximately constant light source is desired. Broad claims to this phase of our invention will be found in our parent application.

50 In one embodiment of our invention, we may place the light source 12, which for example may be an incandescent globe of any desired type, in a chamber with double walls such as 70 and 71, and preferably with an air space 72 between them. Fresh air is forced into this chamber 72 by a fan 73 rotative upon a shaft 74 to which is attached a pulley 75, and such air takes the direction shown by the arrows. The pulley 75 may be driven in any desired way, not shown. Through the opening 76 past the baffle plate 77 the fresh air is directed into the inner lamp chamber. The wall 70 being preferably of a heat conductive material, the fresh air, while considerably cooler than the body of air in the 65 chamber, is not of a temperature sufficiently low to cause a drop in the incandescence of the lamp. The heated air leaves the chamber through the vent 78 in the top, which is protected by baffle plates, not shown, as is well known in the projection art, to prevent the escape of objectionable light. This construction per se is claimed in our parent application.

60 Under some conditions the fan 73 may be dispensed with, sufficient circulation of air being 75

obtained by the heat generated within the chamber.

Light is passed from the source 12 through the optical element 79 which may form the window, as it were, of the lamp chamber. Such optical element may be a plate of plane glass or quartz, merely to complete the enclosure of the chamber, or it may be a suitable condensing lens or filter. A mirror or other reflecting surface 80 may be provided.

In order positively to maintain the lamp 12 at a given point of incandescence by holding the temperature of the chamber at a predetermined point, a thermostatic element 81 may be provided which, through an appropriate electrical means, controls the amount of current which is permitted to flow into the heating units 82 which may be placed within the chamber.

The thermostatic control of the circuits of the heating units 82 may be accomplished in any of various well known ways. For example, the thermostatic element 81 may be in circuit with the magnetic element 83 which determines the movement of the wiper arm 84 so that it places more or less of the resistance 85 in circuit with the heating elements 82, thus determining their activity.

It will be understood that we do not limit ourselves to this type of control unit and refer to it merely for purposes of illustration.

In order to compensate for changes in incandescence of the light source which might be brought about by changes in the temperature of the lamp chamber, or lamp house as it is generally termed in the motion picture art, we may regulate the amount of current reaching the lamp in accordance with the temperature of the immediate vicinity of the lamp. Such means may be employed independently of the heat maintaining means just described, or in conjunction therewith. For simplicity, we illustrate this phase of our invention in Figure 7, which also illustrates such heat maintaining means.

A thermostatic element 86 may be provided which controls the amount of current which is permitted to flow into the light source 12. As is later set out in further detail, such control is exercised within restricted limits. The thermostatic control of the circuit supplying the source 12 may be accomplished in any of various well known ways. For example, the thermostatic element 86 may be in circuit with the magnetic element 87 which determines the movement of the wiper arm 88 so that it places more or less of the resistance 89 in circuit with the light source 12. The range within which the current reaching the lamp is permitted so to fluctuate is very small. When a light source, particularly an incandescent light source, is operated reasonably near its point of optical efficiency, a relatively small fluctuation in the current reaching such source will have relatively great effect in the intensity of its light output. It will be understood that since uniformity and not intensity is desired, it is preferable to burn the lamp at a point well below that at which injury to the filament is likely. We prefer that the maximum current permitted to reach the lamp by the resistance 89 be sufficiently restricted so that even when the filament is cold such maximum current will not be dangerous to the life of the filament.

As an additional safeguard, to prevent overloading of the circuit supplying the light source, we may place in such circuit an automatic circuit breaker 90, or other similar device, or the

light source 12 may be fed direct from a battery on the line. This control element will positively prevent any amount of current, over the predetermined maximum, reaching the light source 12.

In those cases in which the heating elements 5 and the means for the control of the circuit of the light source are jointly used, it will be readily understood that the usefulness of the latter means generally will be greater in the early stages of any period of operation. After the temperature of the lamp chamber has been brought to the desired point, it will generally be so maintained by the heating elements alone.

It will be readily understood by those skilled in the art that the joint operation of these two 15 means involves no conflict. From the time of beginning operation until the temperature of the lamp chamber reaches the predetermined point, the thermostatic element 81 will operate gradually to increase the amount of resistance 85 in 20 circuit with the heating elements 82 and so render them less and less active. From that point outwardly, the fluctuations of current in the circuit feeding the heating elements 82 will be such as 25 are necessary to maintain that predetermined point of temperature. It is understood that the ventilating device such as heretofore described when the heating units 82 are entirely inactive will prevent the temperature of the chamber 30 from reaching a point higher than the predetermined point.

When operations begin, all resistance 89 will be out of the circuit feeding the light 12, it if desired being protected against overloading as by the element 90. As the temperature of the chamber increases, the amount of such resistance 89 in circuit with the light source 12 gradually increases until the entire amount is in circuit when the temperature reaches the predetermined point. Should such temperature rise still further, as is 40 not contemplated owing to the above described ventilating system, there would be no change in the amount of such resistance 89 in circuit. Should such temperature fall, the amount of resistance 89 would be decreased until the light 45 source 12 receives the entire amount of current delivered from the line as through the protective device 90. The range of the resistance 89, it will be understood, is carefully limited in accordance with the closely limited range in which current 50 fluctuations occur.

It will be understood by those skilled in the art that while our invention is of particular usefulness under conditions under which the sound and pictorial images are simultaneously recorded, 55 duplicated, and reproduced, it is of great usefulness when the sound and pictorial images during a portion of the entire process are handled separately and successively, later being combined.

It will thus be apparent that the method and 60 construction above described provide extremely simple means whereby sound waves may be accurately and effectively translated into photographic images.

Other advantages have been referred to 65 throughout the specification from which it becomes apparent that different embodiments of the invention may be made within the scope of the inventive disclosure hereof.

We claim:

1. The method of recording sound and pictorial images upon a single light sensitive film which consists in varying monochromatic light in accordance with the sound which is being recorded, passing such light through a slit and upon the film 75

for implanting thereupon images representing such sound, using polychromatic light for implanting thereupon such pictorial images, and concurrently rendering both of such images 5 stable and visible.

2. The method of recording sound and pictorial images which comprises exposing one portion of a light sensitive film to light which varies in accordance with the sound which is being recorded for implanting thereupon images representing such sound and limiting such light to ultra violet, exposing a different portion of said film to polychromatic light for implanting pictorial images thereupon, and concurrently rendering both of such images stable and visible.

3. The method of recording sound and pictorial images which consists in exposing one portion of a light sensitive film to light of a wave length of approximately 4000 Angstrom units which varies 10 in accordance with the sound which is being recorded for implanting thereupon images representing such sound and exposing a different portion of said film to polychromatic light for implanting pictorial images thereupon and concurrently rendering both of such images stable and visible.

4. The method of recording sound and pictorial images which comprises passing light through a slit and upon light sensitive material, varying 15 such light in accordance with the sound to be recorded, limiting such light to rays which vibrate at substantially the same rate thereby minimizing the effect of chromatic dispersion caused by said slit, utilizing polychromatic light for implanting upon another and selected portion of said light sensitive material such pictorial images, and concurrently rendering both of such images 20 stable and visible.

5. The method of recording and reproducing 25 sound and pictorial images upon a single light sensitive film which consists in utilizing monochromatic light which varies in accordance with the sound which is being recorded for implanting thereupon the images representing such sound 30 and polychromatic light for implanting thereupon such pictorial images, concurrently rendering both of such images stable and visible, and concurrently passing light through both sets of such images whereby such sound and pictorial 35 images are concurrently reproduced.

6. The method of recording and reproducing sound and pictures which comprises exposing certain selected portions of a light sensitive film to the action or objects which it is desired to 40 record for visual reproduction and exposing other selected portions thereof to monochromatic light which varies in accordance with the sound which it is desired to reproduce for audible reproduction concurrently with such visual reproduction, rendering the latent images so produced in both such 45 portions stable and visible, and simultaneously reproducing both of said portions by concurrently passing monochromatic light through said images representing sound and polychromatic 50 light through said images representing action or objects whereby the images of action or objects and the images of sounds are concurrently reproduced.

7. The method of recording sound which consists in taking a light sensitive film, causing light 55 which falls within a predetermined range of wave lengths to vary in accordance with the sound to be recorded and to fall upon said light sensitive film thereby producing latent images, developing 60 the latent images so produced, using polychromatic light to record upon the same light sensitive film images of objects or things which it is desired to reproduce concurrently with the reproduction of such sound, simultaneously developing the latent images so produced, printing said film by passing light of a selected wave length through said 65 images representing objects or things and upon a second light sensitive film thereby producing latent images and by passing polychromatic light through said images representing 70 objects or things and upon the same light sensitive film thereby producing latent images, simultaneously developing the latent images so produced upon said second mentioned film, projecting light of a selected wave length through said 75

5 light to record upon the same light sensitive film images of objects or things which it is desired to reproduce concurrently with the reproduction of such sound, simultaneously developing the latent images so produced, printing said film by passing light of a selected wave length through said images representing sound and upon a second light sensitive film thereby producing latent images and by passing polychromatic light through said images representing objects or things and upon the same light sensitive film thereby producing latent images, simultaneously developing the latent images so produced upon said second mentioned film, projecting a constant light of a selected wave length through said 10 stable and visible images representing sound upon said second mentioned film and upon a material the electrical characteristics of which vary in accordance with said light impinging thereupon and simultaneously passing polychromatic light through said images representing objects or things whereby said sound and said objects or things which have been previously recorded are simultaneously reproduced.

8. The method of recording sound which consists in taking a light sensitive film, causing light which falls within a predetermined range of wave lengths to vary in accordance with the sound to be recorded and to fall upon said light sensitive film thereby producing latent images, developing 15 the latent images so produced, using polychromatic light to record upon the same light sensitive film images of objects or things which it is desired to reproduce concurrently with the reproduction of such sound, simultaneously developing the latent images so produced, printing said film by passing light through said images representing sound and upon a second light sensitive film thereby producing latent images and by passing light through said images representing objects or 20 things and upon a second light sensitive film thereby producing latent images, simultaneously developing the latent images so produced upon said second mentioned film, projecting light of a selected wave length through said stable and visible images representing sound upon said second mentioned film and upon a material the electrical characteristics of which vary in accordance with said light impinging thereupon and simultaneously passing polychromatic light through said 25 images representing objects or things whereby said sound and said objects or things which have been previously recorded are simultaneously reproduced.

9. The method of recording sound which consists in taking a light sensitive film, causing light which falls within a predetermined range of wave lengths to vary in accordance with the sound to be recorded and to fall upon said light sensitive film thereby producing latent images, developing 30 the latent images so produced, using polychromatic light to record images of objects or things which it is desired to reproduce concurrently with the reproduction of such sound, developing the latent images so produced, printing said film by passing light of a selected wave length through said images representing sound and upon a second light sensitive film thereby producing latent images and by passing polychromatic light through said images representing 35 objects or things and upon the same light sensitive film thereby producing latent images, simultaneously developing the latent images so produced upon said second mentioned film, projecting light of a selected wave length through said 40 images representing objects or things whereby said sound and said objects or things which have been previously recorded are simultaneously reproduced.

9. The method of recording sound which consists in taking a light sensitive film, causing light which falls within a predetermined range of wave lengths to vary in accordance with the sound to be recorded and to fall upon said light sensitive film thereby producing latent images, developing 45 the latent images so produced, using polychromatic light to record images of objects or things which it is desired to reproduce concurrently with the reproduction of such sound, developing the latent images so produced, printing said film by passing light of a selected wave length through said images representing sound and upon a second light sensitive film thereby producing latent images and by passing polychromatic light through said images representing 50 objects or things and upon the same light sensitive film thereby producing latent images, simultaneously developing the latent images so produced upon said second mentioned film, projecting light of a selected wave length through said 55 images representing objects or things whereby said sound and said objects or things which have been previously recorded are simultaneously reproduced.

stable and visible images representing sound upon said second mentioned film and upon material the electrical characteristics of which vary in accordance with said light impinging thereupon and simultaneously passing polychromatic light through said images representing objects or things whereby said sound and said objects or things which have been previously recorded are simultaneously reproduced.

10. The method of recording and reproducing sound and pictorial images which consists in exposing a selected portion of a light sensitive film to light of a selected wave length which varies in accordance with the sound which is being recorded and in exposing other selected portions of said film to polychromatic light for recording thereupon said pictorial images; developing both sets of latent images so produced, printing said film by passing light therethrough and upon a light sensitive film and developing the latent images so produced upon said second mentioned film, and thereafter projecting a constant light through the portion of said second mentioned film which bears said sound images, the source for said light being positioned in a chamber the temperature of which is maintained at a predetermined level, and upon material the electrical characteristics of which vary in accordance with the light impinging thereupon, and simultaneously projecting polychromatic light through said pictorial images whereby said pictorial images and said sound images are simultaneously reproduced.

11. The method of recording and reproducing sound and pictorial images which consists in exposing certain selected portions of a light sensitive film to light of a selected wave length which varies in accordance with the sound which is being recorded, exposing other selected portions of said film to reproduce thereupon pictorial images, simultaneously developing both sets of latent images so produced, printing said film by passing light therethrough and upon a light sensitive film and developing the latent images so produced upon said second mentioned film, and thereafter projecting a constant light through the portion of said second mentioned film bearing said sound images, said light being maintained at a predetermined level of such characteristics that the light emitted has wave lengths falling within a predetermined range, and upon a material the electrical characteristics of which vary in accordance with said light impinging thereupon, and simultaneously passing polychromatic light through the portion of said second mentioned film bearing said pictorial images and upon a screen whereby said sound and pictorial images previously recorded are reproduced.

12. The method of recording and reproducing sound and pictorial images which consists in exposing certain selected portions of a light sensitive film to light of a selected wave length which varies in accordance with the sound which is being recorded, exposing other and relatively differently placed portions of a film to reproduce thereupon pictorial images; developing both sets of latent images so produced, combining both of said sets of images upon another light sensitive film and developing the latent images so produced upon said second mentioned film, and thereafter projecting light of wave lengths falling within a predetermined range through the portion of said second mentioned film bearing said sound images, and upon a material the electrical characteristics of which vary in accordance

with said light impinging thereupon and passing polychromatic light through the portion of said second mentioned film bearing said pictorial images and upon a screen whereby said sound and pictorial images previously recorded are reproduced.

13. The method of recording and reproducing sound and visible images of objects or things which consists in projecting light of a selected wave length which varies in accordance with the sound which is being recorded through a slot and thereafter through a positive lens and upon certain selected portions of a light sensitive film; exposing other selected portions of said light sensitive film to polychromatic light for the creation thereupon of latent images of objects or things; developing both sets of latent images so produced; printing said film by passing light through both of said portions and upon a light sensitive film and developing both sets of the latent images so produced upon said second mentioned film; thereafter projecting a constant light of a selected wave length through a slot and through those portions of said second mentioned film which bear images representing sound and thereafter through a negative lens and upon a material the electrical characteristics of which vary in accordance with said light impinging thereupon; passing an electrical current through said material and using the variations so produced to reproduce the sound previously recorded; and simultaneously with said previously defined projection projecting polychromatic light through said visible images and upon a screen whereby said sound and said visible images previously recorded are simultaneously reproduced.

14. The method of recording and reproducing sound and visible images of objects or things which consists in projecting light of a selected wave length which varies in accordance with the sound which is being recorded upon certain selected portions of a light sensitive film; exposing other selected portions of said light sensitive film to polychromatic light for the creation thereupon of latent images of objects or things; developing both sets of latent images so produced; printing said film by passing light through both of said portions and upon a light sensitive film and developing both sets of the latent images so produced upon said second mentioned film; thereafter projecting light of a selected wave length through those portions of said second mentioned film which bear images representing sound and upon a material the electrical characteristics of which vary in accordance with the light impinging thereupon; passing an electrical current through said material and using the variations so produced to reproduce the sound previously recorded; and simultaneously with said previously defined projection projecting polychromatic light through said visible images and upon a screen whereby said sound and said visible images previously recorded are simultaneously reproduced.

15. The method of recording and reproducing sound and pictorial images; which comprises exposing one portion of a light sensitive film to light of a selected wave length which varies in accordance with the sound which is being recorded; and exposing a different portion of said film to the action or objects which it is desired to record and reproduce as pictorial images; developing concurrently both such series of latent images so produced; duplicating said film by passing light of a selected wave length through

- the portion of said film which bears such sound images and upon one portion of a second light sensitive film and passing polychromatic light through the portion of said film which bears such 5 pictorial images and upon another portion of said second film; developing concurrently the latent images so produced upon said second film; and thereafter projecting constant light of a selected wave length through the portion of said 10 second film which bears said sound images and upon a material the resistance of which to an electrical current varies in accordance with the light impinging thereupon whereby sound corresponding to that sound which has been so recorded is reproduced and projecting polychromatic light through said other portion of said second film bearing said pictorial images thereupon and upon a screen whereby said pictorial images are reproduced.
- 15 16. The method of recording and reproducing sound and pictorial images which comprises exposing one portion of a light sensitive film to light of a selected wave length which varies in accordance with the sound which is being recorded; and exposing a different portion of said film to action or objects which it is desired to record and reproduce as pictorial images; developing both such series of latent images so produced; duplicating said film upon a second 20 film; developing the latent images so produced upon said second film; and thereafter projecting constant light of a selected wave length through the portion of said second film which bears said 25 sound images and upon a material the resistance of which to an electrical current varies in accordance with the light impinging thereupon; whereby sound corresponding to that sound which has been so recorded is reproduced and projecting light through said other portion of said second film bearing said pictorial images thereupon and upon a screen whereby said pictorial images are reproduced.
- 30 35

cordance with the light impinging thereupon; whereby sound corresponding to that sound which has been so recorded is reproduced and projecting polychromatic light through said other portion of said second film bearing said pictorial images thereupon and upon a screen whereby said pictorial images are reproduced.

17. The method of recording and reproducing sound and pictorial images which comprises exposing one portion of a light sensitive film with 10 an emulsion of a speed between 120 and 200 according to the rating of Hurter and Driffield to light of a wave length of approximately 4000 Angstrom units which varies in accordance with the sound which is being recorded; and exposing 15 a different portion of said film to action or objects which it is desired to record and reproduce as pictorial images; developing concurrently both such series of latent images so produced; duplicating said film upon a second film; developing 20 the latent images so produced, upon said second film; and thereafter projecting constant light through the portion of said second film which bears said sound images and upon material the 25 resistance of which to an electrical current varies in accordance with the light impinging thereupon; whereby sound corresponding to that sound which has been so recorded is reproduced and projecting light through said other portion of said second film bearing said pictorial images 30 thereupon and upon a screen whereby said pictorial images are reproduced.

CARL LOUIS OSWALD.
WARREN DUNHAM FOSTER. 35

CERTIFICATE OF CORRECTION.

Patent No. 2,055,261.

September 22, 1936

CARL LOUIS OSWALD, ET AL.

It is hereby certified that error appears in the printed specification of the above numbered patent requiring correction as follows: Page 1, second column, line 31-32, for "sesure" read secure; page 4, second column, lines 55 and 58, in the table, for "grams" read grains; page 5, second column, line 20, for "of" read or; and that the said Letters Patent should be read with these corrections therein that the same may conform to the record of the case in the Patent Office.

Signed and sealed this 16th day of February, A.D. 1937.

(Seal)

Henry Van Arsdale
Acting Commissioner of Patents.
